UNITED STATES PATENT OFFICE.

TOM ALFRED WOOLLDRIDGE AND ERNEST ALFRED WARD, OF BIRMINGHAM, ENGLAND.

FLEXIBLE COUPLING.

No. 809,880.

Specification of Letters Patent.

Patented Jan. 9, 1906.

Application filed 24, 1905. Serial No. 257,269.

To all whom it may concern:

Be it known that we, TOM ALFRED WOOLLDRIDGE and ERNEST ALFRED WARD, subjects of the King of Great Britain, trading as the 5 Spring Bending Company, of 101^A Alfred road, Handsworth, Birmingham, England, have invented certain new and useful Improvements in Flexible Couplings, of which the following is a specification.

This invention has reference to couplings principally for connecting together articles or lengths of spirally-coiled wire, such as for attaching flexible or open-coiled wire fore ends or nose-pieces to the closely-coiled body 5 parts of instruments for cleaning or removing obstructions from chimneys, flues, and other passages; also for flexibly connecting together the canes of chimney and flue sweeping brushes and for connecting brushes, 10 cutters, boiler-tube scrapers, or other tools to flexible carriers or handles formed from coiled wire or from canes or the like; also for coupling together lengths of flexible shafting formed from coiled wire, and generally for 15 uniting various coiled-wire lengths or articles or articles which are provided with coils for the purpose of effecting their connection to flexible or spirally-coiled carriers.

Figure 1 of the accompanying drawings 30 represents the application of our invention to the connection of a flexible fore end or pilot nose-piece *a* to the body *b* of a drain-cleaning instrument in which the said pilot end is formed from an open coil of wire, while the 35 body is made from closely-wrapped or closely-coiled wire. Fig. 2 is a sectional view, and Fig. 3 shows the pilot-nose and body part separated or detached from one another.

In this particular arrangement the body 40 part *b* is formed with a closely-coiled shank extension or stem *c* of an outside diameter equal to the inside diameter of the body, and this stem, which may either be slightly conoidal a portion of its length or cylindrical 45 in contour, constitutes, as it were, a sprigot and is forced or interscrewed or twisted into the socket-like open end *d* of the pilot-piece, whose coils are thereby slightly expanded or 50 opened out, so that by their contractile reaction upon the coils of the said stem the two

parts or lengths are held together in such a manner that while they cannot be withdrawn or separated longitudinally or by torsionally-applied force or twisting strains the connection is a perfectly flexible one and will 55 not interfere with the bending of either coil in any direction. The same connection may be employed for uniting or coupling two lengths of coiled wire by forming at one end of one length a close-coiled shank or sprigot-like part of a diameter which will admit of the same being interscrewed into the open end of the other part and interlocked by the contractile action of the coils. In the case of 60 connections for securing sweeping, scraping, 65 or cutting tools to holders or carriers formed from coiled wire the tool is formed with or attached to a close-coiled shank for interscrewing into the coiled end of the holder, while when applied as a union or connection for securing together the flexible canes of chimney-sweeping brushes, drain-cleaners, and the like one end of each cane or length is fitted with the coiled-wire socket member of the joint, while the other end is arranged to 70 carry the close-coiled sprigot or peg member. The application of this part of the invention to various other purposes differs in no essential 75 respect from its application to the particular appliances above described.

Having fully described our invention, what we desire to claim and secure by Letters Patent is—

A flexible coupling comprising two closely-coiled members, one of said members terminating in a closely-coiled expansible shank having a portion of its length substantially conoidal in contour and the remaining portion cylindrical, said cylindrical portion of 85 said shank adapted to extend in the other of 90 said members so as to interlock therewith, thereby connecting the members together.

In testimony whereof we have hereunto set our hands in presence of two subscribing witnesses.

TOM ALFRED WOOLLDRIDGE.
ERNEST ALFRED WARD.
